INTERNAL COMBUSTION ENGINE

Filed July 1, 1931

FIG. 1

FIG. 2

Inventor
HERBERT C. EDWARDS.

By *Merton T. Miller*

Attorney

UNITED STATES PATENT OFFICE

HERBERT C. EDWARDS, OF DETROIT, MICHIGAN, ASSIGNOR TO PACKARD MOTOR CAR COMPANY, OF DETROIT, MICHIGAN, A CORPORATION OF MICHIGAN

INTERNAL COMBUSTION ENGINE

Application filed July 1, 1931. Serial No. 548,167.

This invention relates to internal combustion engines and more particularly to valve means therefor.

With some types of internal combustion engines, it is requisite that the fuel charge pass quickly into the cylinder in a definite direction and in an uninterrupted manner in order to provide for efficient operating conditions. This is particularly true in engines 10 of the compression-ignition type in which air is drawn through an intake passage into the combustion chamber within the cylinder in a definite direction, so as to produce rotation thereof, and to adequately fill the cylinder. 15 Ordinarily, when the intake port extends through the head of a cylinder the valve stem traverses a portion of the intake passage, and the usual form of circular valve stem interferes to some extent with the flow of the 20 air into the cylinder so that the desired direction of flow is disturbed and the volume of air which can be drawn through the passage in a given time during the engine operation is reduced.

25 An object of the invention is to overcome the above objections to the usual form of valve mechanism, whereby the same is formed to offer minimum resistance to air flow passing into the cylinders.

30 Another object of the invention is to provide an engine with a valve mechanism which is stream-lined where it traverses the intake passage.

35 A further object of the invention is to stream-line the valve stem bearing sleeve so that the portion thereof projecting into the air inlet passage will offer a minimum resistance to the flow of air.

40 Still another object of the invention is to provide an engine valve having a stem which is stream-lined.

45 Other objects of the invention will appear from the following description taken in connection with the drawing, which forms a part of this specification, and in which:

Fig. 1 is a vertical sectional view of the upper portion of a cylinder having my invention associated therewith;

50 Fig. 2 is a sectional view of the same taken on line 2—2 of Fig. 1;

Fig. 3 is another sectional view of the same taken on line 3—3 of Fig. 1.

Referring now to the drawing by characters of reference, 10 indicates one of the cylinders of an internal combustion engine of the Diesel or compression-ignition type having an end wall or dome 11 formed integrally therewith. A head 12 is detachably secured by bolts 13 upon the dome, and both the cylinder and the head are formed with fins for increasing the heat transfer surface thereof. 60

Within the cylinder is mounted a reciprocable piston 14, and pivotally associated with the piston is a connecting rod 15 of conventional type. 65

A substantially straight Venturi passage 16 extends through the dome and the head at an angle to the axis of the cylinder and tangentially of the inner wall thereof. This passage, in the present instance, serves as the air inlet and as the exhaust outlet; however, duplicate passages and valve mechanism of the character shown and described can be employed. At the inner end of the passage is fixed a hardened valve seat 17. 70

The stem 18 of a poppet valve extends through a portion of the head and the dome, and the head 19 of the valve is movable interiorly of the cylinder and adapted to engage the seat member 17. The valve stem traverses the inner end of the passage 16 and is mounted in a bearing sleeve 20 which is carried by the head and also partially traverses the passageway. 75

In the present invention, the valve is open during the air intake and exhaust strokes and is closed during the compression and working strokes of the piston, it being understood that the engine is of the four-cycle type. Spring means as indicated at 21, arranged in the cylinder head, normally maintain the valve closed in the usual manner and suitable engine operated mechanism (not shown) can be employed for mechanically opening the valve, such valve actuating mechanism being of any conventional character. 85

Extending through the wall of the cylinder is a fuel injection nozzle 22 which is arranged to project atomized liquid fuel under high pressure into the compressed air charges 100

in the cylinder when the piston is near the end of its compression stroke. Through the arrangement of the passage 16, air will be introduced into the cylinder through a space defined by one side of the valve head and the valve seat 17, and due to the angular and tangential position of the valve air in the cylinder will rotate when compressed so that projection of the liquid fuel therein will cause uniform intermingling to produce a mixture which will readily ignite by the heat of compression.

Ordinarily, the sleeve 20 and the valve stem 18 are circular in cross section and in this instance they are of such form except for that portion which projects into or through the passage 16, and it is obvious that there will be interruption of the air flow tending to disrupt the stream movement thereof so as to interfere somewhat with the rotational direction of flow in the cylinder, and also that there is a certain reduction, caused thereby, of the volume of air which can be drawn through the passage during the suction stroke of the piston. In order to reduce such conditions to a minimum, I propose to stream-line that portion of the sleeve and the valve stem which projects into or through the passage 16. Preferably the portion 23 of the sleeve is made of a reduced diameter transversely of the direction of the air flow and the ends thereof are rounded to present a stream-line effect. Likewise, a portion 24 of the valve stem adjacent the head which protrudes beyond the bearing when the valve is wide open is reduced in diameter transversely of the direction of the air flow to present a stream-line section. Both the stream-lined portions of the sleeve and the stem extending into the passage 16 present a narrow width to the air flowing into the cylinder through the passage and to the exhaust flowing out of the cylinder through the passage. This manner of forming the valve stem and the bearing will materially increase the efficiency of the engine

through an increase in the air volume and decreased interference with the intended direction of the air flow.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. In an engine having a passage, a valve controlling flow through the passage, the stem portion of said valve traversing the passage and being of reduced diameter transversely of the direction of flow in the passage and stream-lined in form.
2. In an engine having a passage for the inlet of air and the outlet of exhaust, a valve controlling flow through the passage, the stem of said valve traversing the passage and being flattened transversely of the opposite directions of flow in the passage.
3. In an engine having a passage, a valve stem bearing sleeve partially traversing the passage, the portion of said sleeve extending into the passage being flattened transversely of the direction of flow through the passage.
4. In an engine having an air inlet passage leading to the interior of a cylinder, valve means traversing the passage, the portions of said valve means traversing the passage being of reduced diameter transversely of the direction of air flow through the passage.
5. In an engine having an air inlet passage extending through the head, a reciprocable valve in the head traversing the passage, and a valve stem bearing sleeve in the head partially traversing the passage, the portions of the sleeve and stem in the passage being reduced in diameter transversely of the direction of air flow.
